UNITED STATES PATENT OFFICE.

GEORGE KEITH, OF LONDON, ENGLAND, ASSIGNOR OF ONE-HALF TO JAMES KEITH, OF LONDON, ENGLAND.

GAS-LAMP.

1,192,430.

Specification of Letters Patent. Patented July 25, 1916.

Application filed January 25, 1916. Serial No. 74,100.

To all whom it may concern:

Be it known that I, GEORGE KEITH, a subject of the King of the United Kingdom of Great Britain and Ireland, and residing at 5 London, England, have invented a certain new and useful Improvement in Gas-Lamps, of which the following is a specification.

This invention relates to incandescent gas lamps, more particularly to inverted lamps 10 for high pressure gas lighting.

The invention renders practicable the use of a nozzle tip composed of material capable of withstanding very high temperatures, entails reduction of the area of metal exposed 15 to the flame and therefore of the emanation of metallic particles, and confers greater assurance against tendency of the flame to light back.

The figure of the accompanying drawing 20 is a vertical section of part of a gas lamp embodying the invention.

As shown, the body A of a preheater is fitted with a mantle-support B. The preheater herein shown by way of example 25 serves for heating the gas and air mixture but for the purpose of the present invention it is immaterial whether the mixture or air alone or gas alone be passed through the preheater. Engaging an internally threaded 30 orifice in the lower end of the preheater body is a bush C, which in the present instance is of refractory material, said bush having near its lower end an internal annular shoulder presenting a seat D, its lower 35 external edge being above and close to the bottom of the mantle-ring-receiving recess formed in the mantle-support B. The nozzle proper or burner tip E, which is composed of metal, such, for example, as nickel 40 and chrome alloy, capable of withstanding very high temperatures, is formed with a tapered shoulder bearing on said seat, and is in screw-threaded or other connection with the lower end of a metal tube F, which may 45 be, for example, of cast iron or aluminium bronze and which extends upwardly into the interior of the preheater. The engagement 50 of the tapered shoulder on the tip with the shoulder on the bush is sufficiently close to prevent passage therebetween of the mixture 55 of gas and air contained within the heater, but the tip E is freely separable from the bush C on the shoulder of which it rests.

It will be understood that the nozzle 56 proper or tip E is not directly connected to

the preheater A, heat collected by the tip E and conducted to the tube F being dissipated partly by radiation from the tube to the preheater and partly transmitted to the cold incoming mixture contacting with the walls of 60 the tube F. The nozzle proper or tip E being shielded by the bush C, which is a poor conductor, the area of its exposed portion is relatively small, so that the nozzle does not collect heat rapidly from the flame. 65 It is thus possible to select for the composition of the nozzle proper a metal capable of withstanding very high temperatures, the selection not being limited to the choice of a metal of good thermal conductivity; the 70 reduction in conductivity being compensated for by the comparative shortness of the path along which the heat travels before it reaches the tube. As the nozzle proper is of less substantial dimensions than the nozzle 75 heretofore employed, the cost of the metal is not a serious factor.

A feature of considerable practical utility is that the bush C can be readily unscrewed, even after the lamp has been heated for a 80 long time, whereas, heretofore, difficulty was sometimes experienced in unscrewing the metal nozzle after it had been in use. As aforesaid, the lower end of the bush C may enter the mantle-ring-receiving recess, so 85 that when the mantle support is screwed up the mantle ring H is lightly held between the support B and the bush C, whereby the mantle is steadied, and the space between the bush C and the mantle-support B is cut off 90 from communication with the flame, the upper portion of the bush being thus screened from excessive heat. As aforesaid, the bush may be of refractory material; the non-conducting property of the bush is, however, of 95 more importance than its heat-resisting property. The nozzle tip E is advantageously formed with an internal annular shoulder I which affords an increased margin of security against any tendency to light 100 back.

What I claim is:—

1. In a gas lamp, in combination, a tube for passage of the mixture of gas and air, a bush supported independently of the tube, 105 said bush formed with an internal shoulder, and a nozzle connected to the tube and supported by the shoulder.

2. In a gas lamp, in combination, a gas and air heater, a refractory bush secured to 110

said heater, said bush formed with an internal shoulder, a tube extending from the interior of said heater into said bush, and a nozzle connected to said tube and supported by said shoulder.

3. In a high pressure incandescent gas lamp, in combination, a mantle-support, a non-conducting bush between which and the mantle-support the mantle may be lightly held, a tube projecting into the bush, and a

nozzle proper connected to the tube and separate from, but supported by, the bush.

In testimony whereof I have signed my name to this specification in the presence of two subscribing witnesses.

GEORGE KEITH.
